Patented Sept. 28, 1976

241,638

MOSQUITO REPELLER

Earl W. Holt, 6731 Hillwood Lane,
Dallas, Tex. 75224

Filed Aug. 25, 1975, Ser. No. 607,477

Term of patent 14 years

Int. Cl. D22—06

U.S. Cl. D22—19

FIG. 1

FIG. 2

FIG. 3

FIG. 4

FIG. 5

FIG. 1 is a front perspective view of a mosquito repeller in accordance with my invention;

FIG. 2 is a rear elevation view thereof;

FIG. 3 is a side elevation view thereof, the other side view being the same;

FIG. 4 is a top plan view thereof; and

FIG. 5 is a bottom plan view thereof.

I claim:

The ornamental design for a mosquito repeller, as shown and described.
